BATHING SUIT

Filed May 23, 1921

UNITED STATES PATENT OFFICE.

JAMES M. COMBS, OF AKRON, OHIO.

BATHING SUIT.

Application filed May 23, 1921. Serial No. 471,730.

To all whom it may concern:

Be it known that I, JAMES M. COMBS, a citizen of the United States, residing at Akron, in the county of Summit and State 5 of Ohio, have invented new and useful Improvements in Bathing Suits, of which the following is a specification.

This invention relates to certain new and useful improvements in bathing suits and 10 life preservers and refers particularly to a bathing suit having inflatable portions which may be employed to support the wearer in the water.

It is an object of the invention to provide 15 a thoroughly practicable bathing suit of simple, inexpensive construction, which will float the wearer upon the water.

Another object is to provide an inflatable bathing suit which when not inflated 20 will have the appearance of an ordinary bathing suit and which may be quickly and conveniently inflated when desired.

A still further object is to provide a bathing suit having pockets and to provide inflatable tubes or bags which may be detachably secured in said pockets so that the 25 same may be removed for repair, replacement or other purposes.

The above and additional objects are accomplished by the novel construction, combination and arrangement of parts herein-after described and illustrated in the accompanying drawings wherein I have shown a preferred embodiment of the invention, it 35 being understood that the invention is capable of various adaptations and that changes, variations and modifications may be resorted to which come within the scope of the claims hereunto appended.

40 In the drawings in which similar numerals of reference have been employed to designate like parts as the same may occur in the several views:

Figure 1 is a front elevational view of 45 a bathing suit constructed in accordance with this invention.

Figure 2 is a fragmentary view showing in horizontal section one of the pockets with an inflated air bag therein.

50 Figure 3 is a front elevational view of an adaptation of the invention.

Figure 4 is a cross sectional view taken as indicated by the line 4—4 of Figure 1.

55 Figure 5 is a fragmentary view showing a portion of the inflatable tubes and the

manner of joining the same to an inflation stem.

Figure 6 is a side elevation of a garment constructed in accordance with this invention. 60

Proceeding now with a detailed description of the invention, a bathing suit constructed in accordance therewith comprises a main body 6 which may be composed of any suitable material such as knitted or woven fabric. An extra ply 7 of fabric is secured to the inner side of the body 6 in the form of a wide belt so as to form a garment, the central portion of which is provided with a double wall. The upper edge 70 of the inner wall 7 is secured to the body 6 by means of the seam 8 which extends entirely around the garment and the bottom of said inner wall 7 is likewise secured to said body 6 by means of the seam 9. The inner wall 7 is additionally secured to the body 6 by a circumferentially extending series of vertically directed, regularly recurring seams 10 and 11. The seam 10 extends downwardly from the seam 8 in 75 spaced parallel relation to each other and terminates in spaced relation to the seam 9. The seam 11 are alternately disposed relative to the seam 10 and extend upwardly from the seam 9 and terminate in spaced 80 relation to the seam 8, thus forming a plurality of pockets which are alternately connected at their upper and lower ends and form a continuous pocket or casing 12. An inflatable tube 13 preferably composed of 90 rubber or other elastic material is placed in the pocket or casing 12 so as to extend around the body of the suit in a series of vertical folds.

I prefer to employ two inflatable tubes 13 each closed at one end and each provided at the other end with an inflation stem 14 which is connected by a Y-member 15 to a tube 16 which is provided with an inflation valve 17. The numeral 18 denotes a pinch clamp which is placed on one of the stems 14 for a purpose hereinafter disclosed. The body 6 is provided with a pocket 19 which is formed on the outside thereof for the purpose of holding the Y-member 15 and the tube 16. 95 The pocket 19 is provided with openings 100 which lead into the pockets 12 and one of the tubes 13 is placed in the pocket 12 so that it extends around the forward part of the body and the other tube is placed in 105 110

said pocket so as to extend around the body in an opposite direction.

In the modification of the invention shown in Figure 3, I have provided a structure which, while practically identical with the structure above described, may be more quickly and more economically manufactured. In this modification, I have provided a jacket portion 6^a and a pants portion 6^b. The pants portion 6^b is extended upwardly and the upper portion thereof is secured to the jacket portion 6^a in exactly the same manner as the inner wall 7 is secured thereto in the structure first above described. The upper edge of the pants portion 6^b is secured to the waist portion by the seam 8 and the jacket portion 6^a and the pants portion 6^b are also connected by the seam 9 and an outer and inner wall is thus formed. The walls are further connected by the vertical seams 10 and 11, thus providing a structure practically identical with the structure first above described.

In use, the tube 16 may be taken from the pocket 19 and conveniently inflated by the wearer, whereupon the pinch clamp 18 is operated. If the wearer then desires to use the suit with only the rear portion inflated, the valve 17 is released and the air in the forward tubes 13 is allowed to escape. If the wearer desires to use the suit with only the forward part inflated the pinch valve 18 is closed before inflation.

Ordinarily the suit is used with both tubes inflated so that a puncture or other injury to the one of the tubes 13 will not effect the buoyancy of the other tube.

While I have shown the extra ply 7 of fabric secured to the inner face of the body 6, it is to be understood that it may, if desired, be secured to the outside of the suit. It is also to be understood that a single tube 13 may be employed and that other changes may be made which come within the scope 45 of the appended claims.

Having thus described my invention what I claim as new and desire to secure by Letters-Patent is:—

1. In a garment of the class described, a

waist portion having an outer and an inner 50 wall, a seam joining said walls at the upper extremity of said waist portion, a seam joining said walls at the lower extremity thereof, said walls further joined by a circumferentially extending series of vertical 55 seams which alternately terminate in spaced relation from opposite extremities of said waist portion, to form a continuous pocket and an inflatable tube in said pocket.

2. In a device of the class described, a 60 jacket portion and a pants portion, the pants portion extending upwardly underneath the jacket portion, and seams joining said portions so as to form a circumferentially extending series of communicating 65 pockets therebetween.

3. In a garment of the class described, a jacket portion and a pants portion, the pants portion extending upwardly underneath the jacket portion, a circumferentially 70 extending seam joining the upper edge of the pants portion to the jacket portion, a second seam joining said portions, said second seam extending around the garment below the first named seam in spaced relation 75 thereto and vertical seams additionally positioned between the first and second named seams so as to form a plurality of communicating pockets.

4. In a garment of the class described, 80 a jacket portion and a pants portion, the pants portion extending upwardly underneath the jacket portion, a circumferentially 85 extending seam joining the upper edge of the pants portion to the jacket portion, a second seam joining said portions, said second seam extending around the garment below the first named seam in spaced relation thereto and vertical seams additionally positioned between the first and 90 second named seams so as to form a plurality of communicating pockets and an inflatable elastic tube positioned in said pockets substantially as and for the purposes herein set forth.

In testimony whereof I have hereunto set my hand.

JAMES M. COMBS.
